United States Patent Office

Des. 181,353
Patented Nov. 5, 1957

181,353

TOY SQUIRT CAMERA

Adolph E. Goldfarb, North Hollywood, and Henry G. Saperstein, Los Angeles, Calif.

Application November 5, 1956, Serial No. 43,660

Term of patent 3½ years

(Cl. D34—15)

Fig. 1.

Fig. 2.

Fig. 3.

Fig. 4.

Fig. 1 is a front elevational view of a toy squirt camera, showing our new design;

Fig. 2 is a side elevational view, the opposite side having substantially the same appearance;

Fig. 3 is a top plan view; and

Fig. 4 is a rear elevational view thereof.

We claim:

The ornamental design for a toy squirt camera, substantially as shown and described.
